DESIGN FOR AN AUTOMOBILE

Carl Breer, Grosse Pointe Park, Mich., assignor
to Chrysler Corporation, Detroit, Mich., a cor-
poration of Delaware

Continuation of applications Serial Nos. 50,063,
50,064, and 50,065, December 13, 1933. This
application June 2, 1934, Serial No. 52,027

Term of patent 14 years

To all whom it may concern:

Be it known that I, Carl Breer, a citizen of the United States, residing at 15600 Windmill Pointe, in the city of Grosse Pointe Park, county of Wayne, and State of Michigan, the inventor of the design embodied in applications, Serial Nos. D-50,063, D-50,064, and D-50,065, filed December 13th, 1933 of which this application is a continuation, have invented a new, original, and ornamental Design for Automobiles, of which the following is a specification, reference being had to the accompanying drawing, forming part thereof, in which:

Fig. 1 is a side elevational view of an automobile showing my new automobile rear end design in full lines and illustrating the front end and intermediate portions of the automobile in dot and dash and dotted lines, respectively.

Fig. 2 is a three-quarter rear perspective view of an automobile showing my new automobile

rear end design in full lines, and illustrating the front end and intermediate portions of the automobile in dot and dash and dotted lines, respectively.

Fig. 3 is a rear end view of an automobile showing my new automobile rear end design, the dotted lines indicating immaterial parts.

The dominant feature of my new design and the portion on which I desire to secure protection comprises the appearance of the rear end portion, as shown in full lines. The front end portion shown in dot and dash lines (Figs. 1 and 2) is illustrative of the subject matter of my co-pending application Serial No. D-52,026, filed on even date herewith.

I claim:

The ornamental design of an automobile substantially as shown, and described.

CARL BREER.
